UNITED STATES PATENT OFFICE

WILLIAM HOWARD MATTHAI, OF GARRISON, MARYLAND

BOTTLE RACK

Application filed May 18, 1932. Serial No. 611,965.

This invention relates to an improved bottle-rack and has for one of its objects to provide a very simple and inexpensive rack which will securely hold a number of bottles for display and other purposes.

Another object is to provide an improved rack of this character wherein the bottles will be pendants hung by their necks in such manner that they will not accidentally be come disengaged.

A further object is to provide an improved bottle-rack for pendants sustaining a number of bottles and which will remain in an upright position regardless of the distribution of the bottles about the rack.

A still further object is to provide an improved construction of bottle-rack wherein the parts may, if desired, be shipped in a knock-down condition and readily assembled by a purchaser.

Another object of the invention is to provide a rack for a number of bottles wherein the bottles will be suspended from their necks, leaving the bottoms free and unsupported so they may be held outwardly in an inclined position, more or less according to their diameters, by a rest-ring which engages them above their bottoms, and thereby enable the rack to accommodate bottles that vary greatly in either diameter or length, such as pint or quart bottles, or both at the same time.

With these, and other objects in view, the invention is illustrated in the accompanying drawing, wherein,—

Fig. 1 shows the improved rack in perspective with two bottles held by their necks in a suspended position and locked in place.

Fig. 2 illustrates in top view, a portion of the notched bottle-suspension plate with the locking-ring in locking position beneath the same, and

Fig. 3 shows a sectional detail through the edge of the notched suspension-plate with one of the supports and the annular bottle-rest ring, together with a bottle suspended from the notched plate and locked in the notch thereof by the locking-ring.

In the drawing the numeral 5 designates the supporting bars whose lower ends are attached to an annular base-ring 6 and whose

upper ends are attached, in a peculiar manner, to a bottle-suspension plate 7 as will presently be more fully explained.

The supporting bars preferably extend upwardly in an inclined converging direction from the base-ring 6 to a point where they are bent to form a short vertical portion 8 and a bottle rest-ring 9 extends around and embraces all of the bars at the vertical portions and this ring also serves to properly space the bars and hold them in rigid relation. While this ring 9 may be attached to the vertical faces of the several bars in any suitable manner, I prefer to employ bolts and nuts 10 and 11 respectively so that the parts may be shipped in a knock-down condition.

The suspension plate 7, in this instance, is smaller in diameter than the annular ring 9 beneath it so that the several supporting bars 5 assume a converging inclined position at 12 from the ring 9 up to the suspension plate 7.

Each supporting-bar has a horizontal shoulder 13 formed therein directly beneath the suspension plate 7 so that said plate may rest upon said shoulders, and adjacent to each of said shoulders the plate 7 has a vertical slot 14 extending therethrough from the lower to the upper side.

Each supporting bar has an up-turned end 15, just beyond its supporting shoulder 13, which end projects up into the slot 14 of the plate so as to lock said upper end of each supporting bar in said slot against twisting strains.

I also attach or secure the plate 7 down on the shoulders 13 of the bars, preferably by short bolts and nuts 16 and 17 respectively, as clearly shown in Fig. 3.

Obviously, the up-turned ends 15 of the supporting bars may be extended up through the slots 14 of plate 7, to a point well above the latter, as indicated by broken lines 18 in Fig. 3, and as there would be at least three of these extensions, they would readily form a holder for a bottle on top of the suspension plate, if the handle 19 were omitted.

The suspension plate 7 is of a generally circular form, having a flat central portion 20 and an endless series of upwardly-inclined

supporting fingers 21 with intervening notches 22 between adjacent fingers, thus producing alternate fingers and notches.

Each supporting finger 21 has an upturned flange 23 at its extreme outer edge, while the base 24 of each notch is rounded to conform substantially to the cross-sectional contour of the bottle-neck.

Most bottles 25 have an enlargement 26 between the mouth and neck, and I have designed my suspension plate to make use of this enlargement in holding the bottles in place in the notches 22 and between the fingers 21 to prevent accidental displacement.

To place a bottle in engagement with my suspension plate, it is necessary to lift the bottle until the enlargement 26 will pass over the upper edge of the up-turned flange 23 at opposite sides of the notch in which the neck is to be inserted, and then pass the reduced portion of the neck in the notch. Then, after the neck has been inserted, allow the bottle to move down until its enlargement seats on the side edges of the fingers at opposite sides of it, at which time the lower part of the enlargement will assume position below the said flanges 23 so the latter will prevent said necks from being displaced unless the bottles are lifted.

The weight, therefore, of the bottle, after the latter is engaged by the fingers, will prevent accidental lateral displacement.

If therefore, the device is to be used to carry a plurality of bottles, such as is frequently done at places of amusement during the sale of liquid refreshments, the bottles will be so engaged at their necks as to prevent their accidental displacement.

When however, the device is to be used as a display rack, and it is desired to lock the bottles in place to prevent theft, I have devised a simple means for effecting this locking which will now be explained.

After the bottles have been inserted in the notches with their sides resting against the annular ring 9 and their bottoms free and unsupported, a band 27 may be placed so as to encircle the necks of all of the bottles, at a point immediately below the suspension plate, and locked in that position. This ring or band 27 is preferably formed in two sections, two ends of which are pivoted together at 28, and the other two ends locked together by means of any suitable lock, such as shown at 29.

The diameter of the band or ring 27 is smaller than the diameter of the suspension plate 7 so that the ring cannot be passed over the fingers 21, as shown in detail in Figs. 2 and 3.

When the band or ring is thus locked in place around the group of bottle-necks, the bottles cannot be manipulated to free their necks from the notches 22 and therefore the bottles will be locked in the rack and cannot

be removed until the locking ring is detached.

The diameter of the suspension plate 7 with respect to that of the ring 9 is such, that the bottles will be held in an inclined position, so that the locking ring or band 27, about the bottle-necks, cannot drop down over the bodies of the suspended bottles. The engagement of the locking ring or band about the bottle-necks also prevents the lower unsupported ends of the bottles from being manipulated to swing them to the inner side of the rest-ring 9 and therefore the bottles cannot be swung together at their lower ends in an effort to release the bottle-necks from the notches of the suspension plate.

The vertical face of either the base-ring 6 or the rest-ring 9 will serve to carry advertising matter in addition to performing their other functions. It will be noted that the rest-ring 9 is of a larger diameter than the suspension points around the plate 20 so that the bodies of the bottles will rest against the outer side of said rest-ring and thus be made to assume an inclined position.

It will also be noted that the location of the rest-ring 9 beneath the suspension plate 20 is such that the ring will engage the inner sides of the suspended bottles above the bottoms of the latter, and that the bottoms of the bottles are free and unsupported.

There is a decided advantage in suspending the bottles from their neck-ends and then providing some means that will engage the inner sides of the bodies of the suspended bottles, above their bottoms, to swing the lower free ends of the bottles outwardly so they will assume an inclined position.

It will be understood that the bottoms of the bottles are entirely free of any bottom support, therefore, the same rack will accommodate bottles that greatly differ in length.

It will further be seen that by employing means, such as the rest-ring 9, to engage the sides of the bottles above the bottoms of the latter, the same rack will accommodate bottles that greatly differ in diameter, for, as the bottles increase in diameter, they will assume a greater inclination from the suspension-plate down.

Thus by combining a neck-suspension plate with a rest-ring to engage the sides of the bottles, above the bottoms of the latter, the same rack will accommodate bottles of either pint or quart capacities, and the same number of bottles may be placed in the rack regardless of whether they are pints or quarts, because, the bottoms are unsupported, and the differences in diameters are automatically taken care of by the freedom of the bottoms to move outwardly away from the rest-ring when the sides of the bottles rest thereagainst.

What I claim is,—

1. In a bottle rack the combination with

an annular suspension-plate having an annular series of alternate suspension fingers and bottle-neck receiving-notches around its periphery for pendants sustaining bottles by their necks and means below said suspension-plate and above the bottoms of the bottles for holding the neck-sustained bottles in an inclined position.

2. In a bottle rack the combination with
10 an annular suspension-plate having an annular series of upwardly-inclined supporting fingers with intervening bottle-neck receiving-notches around its periphery, of means for sustaining the suspension-plate in an ele-
15 vated position whereby the bottles may be pendants sustained from their necks and means below the suspension-plate and above the bottoms of the suspended bottles for en-
gaging the sides of the bottle above the bot-
20 toms of the latter and holding the neck-sus-
pended bottles in an inclined position.

3. In a bottle rack the combination with an annular suspension-plate having bottle-neck receiving notches around its periphery for
25 pendants sustaining bottles by their necks, of a plurality of bars engaging said suspension-plate to support the same in an elevat-
ed position and a band extending around and engaging said bars,—said band forming a
30 support at the inner sides of the suspended bottles well above the bottoms of the latter to hold the latter in inclined suspended posi-
tions with respect to the vertical axis of the rack.

35 In testimony whereof I affix my signature.
WILLIAM HOWARD MATTHAI.
